UNITED STATES PATENT OFFICE

DAVID F. QUIGLEY, OF BROCKTON, MASSACHUSETTS, ASSIGNOR TO CONRAD SHOE COMPANY, OF BROCKTON, MASSACHUSETTS, A CORPORATION OF MASSACHUSETTS

DESIGN FOR A SHOE

Application filed June 16, 1930. Serial No. 36,049. Term of patent 14 years.

To all whom it may concern:

Be it known that I, DAVID F. QUIGLEY, a citizen of the United States, residing at Brockton, in the county of Plymouth and State of Massachusetts, have invented a new, original, and ornamental Design for Shoes, of which the following is a specification, reference being had to the accompanying drawing, forming part thereof.

I claim:

The ornamental design for a shoe, as shown.

DAVID F. QUIGLEY.
